Atty's

UNITED STATES PATENT OFFICE.

MAX G. PAULUS, OF WHITING, INDIANA, ASSIGNOR TO STANDARD OIL COMPANY, OF WHITING, INDIANA, AND CHICAGO, ILLINOIS, A CORPORATION OF INDIANA.

APPARATUS FOR DISTILLING HYDROCARBON OILS.

Application filed July 28, 1920. Serial No. 399,568.

To all whom it may concern:

Be it known that I, MAX G. PAULUS, a citizen of the United States, residing at Whiting, in the county of Lake and State of Indiana, have invented a new and useful Improvement in Apparatus for Distilling Hydrocarbon Oils, of which the following is a specification.

The present invention relates to the distillation of hydrocarbon oils and more particularly to the pressure distillation of high boiling point oils for the pyrogenesis of lower boiling point oils. It will be clearly understood from the following description 15 of a specific embodiment thereof, illustrated by the accompanying drawing, in which:

Fig. 1 is an elevation, partially in section, of a still suitable for carrying out the invention; and

Fig. 2 is a detail sectional view through a portion of the lower header, showing the connections of the tubes therewith.

Referring more particularly to the drawing, the numeral 5 indicates a bulk supply 25 container or drum, preferably lagged, which may be of the horizontal shell or cylindrical type and which is provided with an outlet vapor line 6, through which charge and feed stock are supplied and reflux from the 30 phlegmators (not shown) may be returned. The drum 5 is mounted on a suitable furnace setting 7, and the legs or pipes 8 and 9 depend substantially vertically from points near its ends. Of these legs or pipes leg 8 35 is longer than leg 9. The legs 8 and 9 communicate with headers 10 and 11 respectively, the former being on a lower level than the latter.

The headers 10 and 11 are connected by a 40 plurality of rows or banks of tubes 12, 12 which are inclined in position and which are directly heated by the combustion gases in the furnace. The deck 13 above the tubes prevents direct heating of the container or 45 drum 5 by the furnace gases. The heating of the upwardly inclined tubes 12, 12 causes a thermal circulation of the oil which fills tubes, headers, legs completely and the drum 5 partially. A draw-off pipe 14 is provided for the removal of distillation residues.

In operation the still is charged with a suitable stock, for example, a gas oil of about 32° Bé. gravity, and heat is applied to cause pyrogenetic conversion of the stock

into lower boiling constituents, such as gasoline, while the still is maintained under an internal pressure of, say, 4 to 6 atmospheres of still gas or of inert gas such as CO₂ or stack gas. A thermal circulation of the oil through the tubes and still takes place by reason of the position and arrangement of the tubes, and maintains the oil in the drum at the elevated temperature desired. Gas, for example an inert permanent gas, such as still gas, stack gas or CO₂, supplied under pressure from main or line 15, passes through pipe 16 into the still and down the longer leg 8 to manifolds 17, 17 in the lower header 10, from which manifolds it is injected through nozzles 18, 18 into the streams of oil in tubes 12, 12 in the direction of flow of the oil through the latter. The gas thus added increases the rate of circulation of the oil through the highly heated zone and serves to maintain in whole or in part the pressure within the still. It discharges through the vapor line 6 and passes through the condenser system as permanent gas. Feed stock, which may be of the same character as the charging stock or may be a higher Baumé gravity stock, if desired, may be fed into the drum 5 through the vapor line during the distillation to maintain substantially a constant level therein.

Although the present invention has been described in connection with a specific example thereof, details as to which are given, it is not intended that these shall be regarded as limitations on the scope of the invention except in so far as included in the accompanying claims.

I claim:

1. In combination, a still setting, a bulk supply container mounted thereon, downwardly inclined circulating tubes mounted in the heated zone of the setting, headers at each end of the tubes, means connecting the headers with the container, and means for injecting gas into the lower ends of said tubes in an upward direction.

2. In combination, a still setting, a bulk supply container mounted thereon, downwardly inclined circulating tubes mounted in the heated zone of the setting, headers at each end of the tubes, means connecting the headers with the container, nozzles projecting into the lower ends of said tubes and means

for supplying gas under pressure to said headers with the container, nozzles projecting into the lower ends of said tubes, manifolds within the lower header to which said nozzles are connected and means for supplying gas under pressure to said headers. 10

3. In combination, a still setting, a bulk supply container mounted thereon, downwardly inclined circulating tubes mounted in the heated zone of the setting, headers at each end of the tubes, means connecting the

MAX G. PAULUS.
